UNITED STATES PATENT OFFICE.

THOMAS TRUEMAN GAFF, OF CINCINNATI, OHIO, ASSIGNOR TO THE CEREALINE MANUFACTURING COMPANY, OF COLUMBUS, INDIANA.

PRESERVING FARINACEOUS PRODUCTS.

SPECIFICATION forming part of Letters Patent No. 388,962, dated September 4, 1888.

Application filed January 15, 1886. Serial No. 188,664. (Specimens.)

To all whom it may concern:

Be it known that I, THOMAS TRUEMAN GAFF, a citizen of the United States, residing at Cincinnati, in the county of Hamilton and State of Ohio, have invented certain new and useful Improvements in the Art of Preserving Farinaceous Products in the Dry State; and I do hereby declare the following to be a full, clear, and exact description of the invention, so such as will enable others skilled in the art to which it appertains to make and use the same.

According to my invention ordinary farinaceous products are inclosed in what I term a "germ-tight" bag, box, or wrapper, and thus inclosed are subjected to a sufficiently high temperature for such a length of time as will suffice to sterilize or deprive of life any germs or eggs or living foreign matter which may have been inclosed with such product in said germ-tight package, whether mixed with such product—being a part of such product—or contained in the inclosed air. By a "germ-tight" package is meant a covering suitably applied which will exclude germs of whatever kind or nature, although not necessarily air-tight or gas-tight. One such material is good Manila paper, which I have successfully used as a wrapper in the preservation of the product from corn, known in the market as "cerealine," described in several United States patents granted to Joseph F. Gent, the first of which patents is numbered 223,847. In preserving cerealine the following method was adopted and proved entirely successful: The cerealine was put in an ordinary paper box. A wrapper of good Manila paper was then pasted on, so as to entirely cover and seal the paper box. Thus wrapped, the package was

put in a steam muffle and subjected for about one hour to a temperature of from 213° Fahrenheit to 215° Fahrenheit. On removal from the steam-muffle a paper label completely covering the germ-tight Manila wrapper was pasted on.

I do not confine myself to any particular temperature, because that may be greatly varied, according to the nature of the product to be preserved and the character of the germ-tight covering. If a higher temperature is employed, the goods are exposed to it for a shorter period. Nor do I confine myself to any particular device for heating packages of farinaceous products for the purpose mentioned, although I recommend the use of a steam-muffle as most convenient. Nor do I confine myself to any particular mode of applying germ-tight coverings, or to any particular number of such coverings, one or more being applied, as may be deemed expedient or required by the character of the said covering.

I claim as my invention—

The art of preserving farinaceous products in a dry state, which consists in inclosing such products in pervious coverings of paper or fabric, and exposing them so inclosed to a baking temperature sufficient to sterilize or deprive of life germs, eggs, or living foreign matter within such covering and retaining the products so inclosed, substantially as described.

In testimony whereof I affix my signature in presence of two witnesses.

THOMAS TRUEMAN GAFF.

Witnesses:

S. S. THOMSON,
JAMES D. PARKER.
